United States Patent Office

Des. 233,870
Patented Dec. 10, 1974

233,870

ARM CHAIR

Richard Goldsmith, 19 Fiske Place,
Brooklyn, N.Y. 11215

Filed Mar. 28, 1973, Ser. No. 345,571

Term of patent 14 years

Int. Cl. D6—01

U.S. Cl. D6—56

FIG. 1 is a front perspective view of an arm chair showing the new design;

FIG. 2 is a front elevation thereof;

FIG. 3 is an elevation of one side thereof, the other side being a mirror image; and

FIG. 4 is a top plan view thereof.

I claim:

The ornamental design for an arm chair, as shown and described.
